JOHN A. HAMLIN, OF UTICA, NEW YORK, ASSIGNOR OF ONE-HALF TO
EMIL J. GEORGE, OF UTICA, NEW YORK.

BOTTLE-STOPPER.

No. 800,208.

Specification of Letters Patent.

Patented Sept. 26, 1905.

Application filed January 30, 1905. Serial No. 243,192.

To all whom it may concern:

Be it known that I, JOHN A. HAMLIN, of Utica, in the county of Oneida and State of New York, have invented certain new and useful Improvements in Bottle-Stoppers; and I do hereby declare that the following is a full, clear, and exact description of the invention, which will enable others skilled in the art to which it appertains to make and use the same, reference being had to the accompanying drawings, and to the characters of reference marked thereon, which form part of this specification.

The object of my present invention is to provide an improvement in bottle-stoppers where-in provision is made for preventing the refilling of the bottle and which is simple and practical in construction and efficient in its operation.

In the drawings which accompany this specification, Figure 1 shows a vertical section of the upper portion of the body, the neck portion of the bottle, and of the stopper and cork of my improved construction. Fig. 2 is a side elevation of the stopper removed from the neck 25 of the bottle. Fig. 3 is a bottom view of the top portion or upper section of the bottle-stopper. Fig. 4 is a bottom or under view of the valve employed in the construction. Fig. 5 shows a modified form of construction of 30 the bottle and neck.

Referring to the reference letters and figures in a more particular description, 1 indicates the body of the bottle provided with the neck 2, which is of a tapering form, particularly as to its inner side or surface, with the enlarged end of the taper toward the or connecting onto the body of the bottle. The bottle-neck includes also a substantially cylindrical portion 2^a, adapted to receive the stopper and the cork. The stopper consists of the three portions or sections 3, 4, and 5, the two former being of ring shape, while the latter is a cap-like plate. The section 3 is provided with a shoulder adapted to rest on the inclined shoulder 6 at the point of juncture between the conical neck portion 2 of the bottle and the cylindrical portion 2^a. The stopper-section 3 has an enlarged central opening, with a beveled or inclined valve-seat 3^a. The section 4 is of a ring form, having a relatively large internal opening or perforation, together with an inwardly-standing flange 4^a, which may be given an upward turn, as shown.

The upper section 5 is provided around its periphery with a series of small holes or openings 5^a to afford passage for the liquid from the bottle. The upper or cap portion 5 is also provided with a central socket 5^b, which receives the upper end of the valve-stem 7^a of the valve 7. The opening in the middle section 4 affords a passage for the valve-stem 7^a, as well as for fluids around the stem. The valve-stem 7^a is provided with a central longitudinal opening which, in connection with the socket 5^b, receives the spring 8, said spring 65 operating to force the valve to closed position on the seat 3^a, but still being a light tension-spring. The stopper parts 3 and 4 join each other with an inclined bearing-face, as indicated at *a*, while the stopper parts 4 and 5 join each other with an inclined engaging face, as indicated at *b*. The parts 4 and 3 are arranged to afford a cavity for the open position of the valve, and the valve is limited in its opening movement by the top of the stem 75 coming in contact with the bottom of the socket 5^b, whereby it is prevented from closing the opening through the part or section 4 when in its open position. The upper section of the stopper has the edge or corner removed, and a groove *c* takes its place, and when in position with the lower end resting on the shoulder 6 the upper edge of the stopper takes a position opposite an internal groove *d* in the cylindrical portion of the 85 neck.

In practice it is found more advantageous to form the stopper from glass, as well as the valve 7, and in order to facilitate such manufacture it is preferably formed in the sections 90 3, 4, and 5 fitting together with the inclined shoulders *a* and *b*, as before mentioned. These will be ordinarily assembled in the form shown in Fig. 2 with the valve and stopper cemented together by some adhesive cement. In 95 this shape they are in convenient form for use.

The bottle will be filled, of course, when the stopper is removed. When it is desired to close the bottle, it is preferably done as follows: The spherical weight 10, preferably a 100 glass ball, is first dropped into the bottle. Then a thin coating of cement will be applied to the inclined shoulder on the lower end of the stopper and the stopper set in position, the said inclined shoulder resting on the 105 shoulder 6. The cavity formed by the groove

d and the groove *c* will then be filled with some liquid cement and the same left to set. After it is set the cork stopper 9 will then be placed in position in the open end, substantially as shown.

While much has been said that the portion *2^a* of the bottle-neck is made cylindrical, this is not absolutely necessary and often a difficult thing to accomplish in practice, and in this connection it should be noted that in case the outer wall of the stopper does not engage the inner wall of the neck opposite thereto that when the liquid cement is introduced it will fill such a cavity as may be, even down to the shoulder 6. In some views of the device it may be advantageous to have the portion of the neck above the shoulder 6 of slight conical form, with the larger end outward.

The most trying situation for devices of this class is when the bottle rests on its side. In this situation the conical form of the neck *2* will cause the weight 10 to roll away from the stopper into the bottle and not interfere with the valve in its closed position.

The operation of discharging the contents of the bottle is quite obvious; but it may be mentioned that when the bottle is in inverted position and the cork stopper 9 having of course been previously removed the weight 10 will fall against the projecting bitted end *7^b* of the stopper and force it into open position. This allows the contents to flow through the passage, which then becomes free, issuing through the openings *5^a*. When the bottle is turned into a horizontal position or to a vertical position, the weight 10 will fall away from the stopper and allow the spring 8 to close the same. It may be noted in this connection that the flange *4^a*, standing opposite the opening *5*, prevents the insertion of any instrument through the openings *5^a* to tamper with the closed position of the valve, also that when the flange *4^a* is provided with an upward turn, as shown, it serves its purpose to better advantage than when simply made straight, as before suggested. It will also be noted that the spring 8, being entirely inclosed with the valve-stem and the socket *5^b*, is also protected from any instrument inserted through the opening *5^a*.

The stopper, consisting of the parts 3, 4, and 5, being made of glass, preferably, as before suggested, it will be noted that with an instrument, as a small punch and hammer, the whole stopper can be crushed and removed, whereby the bottle becomes useful for ordinary purposes in connection with a common cork stopper; but when so used it is evident from the absence of the glass stopper that it has been refilled.

In the modified form of construction shown in Fig. 5 the bottle-neck has been modified by forming a contracted opening *n* at the base

of the neck, which is adapted to receive the weight 10 and prevent it falling into the body 65 of the bottle when the body is in upright position. In this case, however, as in the former, the neck is made of conical form, whereby the weight is adapted to move away from the valve when the bottle is in a horizontal position.

What I claim as new, and desire to secure by Letters Patent, is—

1. The combination of a bottle having a tapering neck enlarging toward the body, an internal shoulder in the neck, a stopper consisting of inner, outer and intermediate sections, the inner section having a large central opening and valve-seat for outwardly-opening valve, the outer section having a series of small openings arranged around the periphery and on the inner side a socket for the valve-stem, the intermediate section having a large central opening affording a passage for the valve-stem and liquids and an inwardly-standing flange affording an obstruction in the line of the perforations of the outer section, a valve having a bitted projection projecting beyond the inner face of the stopper when seated, and a tubular stem engaging with the outer section, and a spring within the tubular stem for forcing the valve to closed position, and a weight inclosed within the bottle, substantially as set forth.

2. The combination of a bottle having a tubular outlet-opening with an internal shoulder adjacent to the inner end of the opening, a stopper seated on the shoulder and located within the opening consisting of three sections, the lower section having a central opening with a surrounding valve-seat, the middle section having an inwardly-standing flange *4^a*, the top section having small perforations *5^a* vertically above the said flange, an outwardly-opening valve *7* adapted to coöperate with said seat, a spring for forcing the valve to closed position confined between the top and lower sections and a weight within the bottle adapted to engage and force the valve into open position when the bottle is inverted, substantially as set forth.

3. The combination of a bottle having a tubular outlet-opening with an internal shoulder adjacent to the inner end of the opening, a stopper seated on the shoulder and located within the opening consisting of three sections, the lower section having a central opening with a surrounding valve-seat, the middle section having an inwardly-standing flange *4^a*, the top section having small perforations *5^a*, vertically above the said flange, and a socket *5^b*, an outwardly-opening valve adapted to coöperate with said seat having a bitted end operating in the opening in the lower section, and a tubular stem the upper end of which is received in said socket *5^b*, a spring

for forcing the valve to closed position arranged within the tubular valve-stem and a weight within the bottle adapted to engage and force the valve into open position when the bottle is inverted, substantially as set forth.

In witness whereof I have affixed my signature,

ture, in presence of two witnesses, this 25th day of January, 1905.

JOHN A. HAMLIN.
